UNITED STATES PATENT OFFICE.

FRIEDRICH WEGMANN, OF ZURICH, SWITZERLAND.

ROLLER-MILL.

SPECIFICATION forming part of Letters Patent No. 294,418, dated March 4, 1884.

Application filed April 25, 1883. (No model.)

To all whom it may concern:

Be it known that I, FRIEDRICH WEGMANN, of Zurich, canton of Zurich, Republic of Switzerland, have invented certain new and 5 useful Improvements in Roller-Mills, of which the following is a specification.

My invention relates to roller-mills for grinding and reducing grain and other substances; and the improvements consist more particularly in automatic mechanism or devices for causing the rolls to be separated and the feeding of material to be stopped whenever the supply of material in the feeding-hopper becomes nearly exhausted.

15 The improvements further consist in various features and details, hereinafter more fully set forth and claimed.

In the accompanying drawings, Figure 1 represents a vertical central section of my improved mill; Fig. 2, a vertical section at right angles to Fig. 1, or longitudinally through the feed mechanism and one of the main grinding-rolls; Fig. 3, an end view of the machine; Fig. 4, a view illustrating the friction-clutch, 25 through which the friction mechanism is thrown into or out of action; Fig. 5, a side elevation of the feeding-hopper and the mechanism for stopping the feed and separating the rolls; Fig. 6, a sectional view of said hopper and feeding-rolls; and Figs. 7 to 14, inclusive, 30 detailed views illustrating the construction and operation of the different parts.

In the practical operation and use of mills of this character it is found that unless great 35 care and attention be given the material to be operated upon will at times become exhausted, permitting the rolls to come into direct contact one with the other, thus greatly injuring their working-surfaces. This injury is particularly noticeable in the case of porcelain 40 rolls, the surfaces being somewhat softer than the surfaces of metal rolls.

Hitherto I have devised and patented mechanism for simultaneously spreading the rolls apart and stopping the feed, said invention being designed to prevent the rolls from running in contact after the feed has stopped, and thus occasioning the injury above referred to; but I find in practice that even this precaution is insufficient, for the reason that unless

close attention is given to the machine the hoppers will at times become empty while the machine continues in motion, thus permitting the rolls to run empty, as before mentioned. I therefore now propose to provide means 55 whereby the rolls shall be separated and the feed stopped simultaneously and automatically whenever the material in the hopper is reduced to a certain predetermined quantity. In this way the rolls are prevented absolutely 60 from at any time running empty while in working adjustment.

Referring now to the drawings, A represents the frame of the machine, consisting of two side castings connected by cross braces or 65 rods *a*, and carrying four axle boxes or bearings, B and C, in which revolve the journals of the two crushing or grinding cylinders. The shaft D of the cylinder E is furnished with a belt-pulley, F, which rotates freely up- 70 on a collar fixed on the shaft D, except when a friction-clutch is caused to lock the pulley to the shaft or axle. The construction of this clutch may be more readily understood by referring to Figs. 2, 4, and 12, in which it will be 75 seen that a head, T, is keyed upon the shaft or axle and formed with a tubular sleeve, which constitutes the axle or journal for the pulley F, so that said pulley may rotate freely upon the sleeve without affecting the shaft D. 80

T' represents a sliding block arranged to move radially through the head T, and provided at its outer end with a shoe, T², the periphery or outer face of which is formed with a series of V-shaped ridges to fit corresponding 85 grooves formed in the inner face of the rim of the wheel F. The sliding blocks T' are connected with a sleeve or collar, F², by means of links or couplings *o*, which are of such length that when the sleeve F² is moved toward the head 90 T the sliding blocks T' and the shoes T² are forced outward and the latter caused to press with great force against the rim of the wheel F. A lever, F', is pivoted to the side of the frame A, and arranged to move the collar to 95 and from the head, according as it is desired to clutch or unclutch the driving-pulley F, two shoes with their operating devices being employed and arranged diametrically opposite each other. 100

By the employment of a friction-clutch I am enabled to stop and start the mill instantly without the shifting of belts, which involves considerable delay, which delay is a matter of 5 great importance in this class of machines, it being essential that in case of derangement of the mechanism, the hopper becoming empty, or of hard substances entering the hopper, the rolls should be instantly thrown out of operation.

By employing a friction-clutch the machine may also be gradually brought into operation, and the severe strain to which it would be subjected by suddenly setting the rolls into motion 15 at full speed is avoided.

No novelty is claimed in the clutch mechanism, which is only present in the case as conducive to a better general understanding of the machine as a whole.

20 The roll E is mounted in fixed boxes or bearings B, and the roll E' is mounted in movable bearings C, carried by swinging arms or supports C', the lower ends of which are sustained by adjustable pivots e. The pivot e has its central portion, on which the arm C' rests, made eccentric to its ends, as shown in Figs. 16 and 17, which ends are seated in holes or sockets in the frame A, so that by rotating the pivot the height of the arms C' may be varied to bring 25 the roll into a true horizontal position and into alignment with its companion roll E.

So far the construction is the same as that described by me in my former application, on which Letters Patent were granted to me, 35 bearing date April 17, 1883, and numbered 276,104. For the purpose, however, of preventing play or movement about the pivot e, by reason of wear of the pivot or of the opening in the arm C', I provide a bearing pin or 40 plug, which is pressed upward against the under side of the pivot by a spiral spring, beneath which is a block, raised or lowered, as required, by a tapered key, e', which is adjusted and held by nuts e. The seat in the 45 arm C', in which the pivot is located, is open at one side, so that the arms may be passed to place or taken therefrom without removing the pivot from the frame, the plate d serving to close the open side of the seat when the arm 50 is in position, said plate being retained by the nuts of the wedge e', the shank of which passes through a hole in the lower end of the plate d.

For the purpose of adjusting the roll E' to and from the roll E, the upper ends of the 55 arms C' are connected by suitable tension devices to depending arms M, secured firmly to a cross-shaft, M', journaled in suitable supports on the main frame, said shaft being furnished with a block, M², provided with a slot 60 to receive a stud or pin, m', on a rocking journal or shaft, m, which is furnished with a hand-lever, R. By moving the hand-lever downward, and thereby rocking the journal m, the stud or pin m' is caused to work in the block 65 M², and thereby to rotate the shaft M' and swing back the arms M, thus releasing the

tension devices and permitting and causing roll-arms C' to swing back and carry the roll E' away from roll E. A spring, n, one end of which is secured to frame A, serves to draw 70 down the arm R when not held against such downward movement.

For the purpose of adjusting the position of the roll E' with great accuracy and nicety, I employ connecting devices (represented in 75 Figs. 5, 8, and 9) between the dependent arms M and the roll-carrying arms C', as shown in Fig. 9. This consists of a frame composed of two longitudinal rods, L, connected at their ends by cross-heads L' and L².

Between the heads, and sliding upon the rods, I arrange four plates, g and g', h and h', and between the plates g and g', which are both free to slide on the rods, I place a strong spiral spring, g², the plate g being arranged to bear 85 directly against the outer face of the arm C', which is preferably furnished with a rubber plug or bearing-block, to avoid undue wear and to deaden the sound of the machine. A compression-screw, g³, provided with a hand-wheel, passes through the cross-head L' and bears against the plate g' to regulate the compression of the spring g², a jam-nut, g⁴, being applied to the screw to prevent its accidental turning.

Between the heads h and h' is placed a lighter spiral spring, h², said spring encircling a telescoping or sliding rod, h³, the two parts of which slide, respectively, through or with the heads h and h', the outer or larger portion of said rod 100 being threaded on its exterior, and provided with a nut, i, and jam-nut, i', whereby the compression of the spring h² may be varied as desired. The spring h² serves to hold the rolls E and E' apart, except as the force of said 105 spring is overcome by the inward pressure of spring g², which is so adjusted as to prevent the actual contact of the rolls, in consequence of the slight play which necessarily exists in the roll-bearings, in order to permit the proper 110 free rotation of the rolls. The rolls are, however, adjusted as close as possible without actual contact for finer grinding or reduction, and the spring h² prevents the movable roll from swinging or falling farther inward than 115 the pressure or force of spring g² compels.

For the purpose of holding the arm R in its upright position, in which position it remains while the roll E is held in working adjustment, I employ a latch or pawl, R', journaled 120 on a spindle or arm, n², which carries at its opposite end an upright arm, R², and a counter-weight, l', the counter-weight serving to cause an engagement of the pawl R' with the nose or forward end of the lever R, as shown 125 in Figs. 5 and 7. The upper end of the arm R² is furnished with a sleeve or collar, l², of leather, rubber, or other material, to prevent the fracture of the arm when struck by the descending weight, as presently described.

Within the hopper I is arranged a gate or valve, K, which is normally held down in the

position shown in Fig. 1 by the weight of grain in the hopper, said gate or valve being hung or sustained at one edge upon a horizontal shaft, P, the end of which is extended past the side of the hopper, and provided with a rigidly-attached arm, Q², carrying a weight, P', and slotted or perforated to permit the passage through it of a rod, Q³, the upper end of which is jointed to a pivoted catch or lever, 10 Q, mounted upon a stud or bearing at the side of the hopper. The catch or arm Q is formed with a hand-piece, as shown in Fig. 5, and serves to engage and hold in an upright position a weight, Q⁴, carried by an arm loosely 15 journaled on the rod or shaft P, the center of gravity of the weight Q⁴ and its supporting-arm being thrown out of line with the axis of the rod or shaft P, so that when the arm or catch Q is raised the weight Q⁴ shall fall by 20 gravity to a point below the rod, and, striking in its course the sleeve or collar l' of the arm R², tips said arm and throws back the dog R', thereby releasing the arm R, permitting the spring n to draw down the said arm, 25 thereby, through the movement of the block M', throwing back the arms M and causing the roll-supporting arms C' to swing outward and carry roll E' away from its companion roll E. So long as the quantity of 30 grain in the hopper is sufficient to overcome the weight P', the gate K will lie down close to the side of the hopper, as shown in Fig. 1, permitting the material to pass freely through the same to the feeding-rolls. Whenever the 35 material falls below a certain point, and thus becomes insufficient to overbalance the weight P', the latter will descend, and, striking a head or enlargement on the rod Q³, will draw the latter down, thereby tipping the dog or lever Q, 40 releasing the weight Q⁴, and permitting the same to fall over and strike the arm R², and thereby to release the dog R' in the manner above explained. It will thus be seen that the operation of the feed-controlling devices is wholly 45 automatic, and that under no circumstances, even during the absence of attendants, can the rolls continue to rotate in their working adjustment when the feed has become exhausted.

When the hopper is again supplied with material, the gate or valve is thereby depressed and the weight P' is raised to relieve the catch or arm Q, permitting the latter to again fall to its operative position. The weight Q⁴ is then again raised by hand to the position shown 55 in Figs. 5, 6, and 7, a shoulder on the arm or catch Q engaging in a notch in the weight Q⁴, and holding the latter in an upright position, as indicated in Fig. 6.

It will be seen by referring to the drawings 60 that the arm Q² is permitted to move some distance before coming in contact with the head or button at the end of the rod Q³, said arm and its weight P' thereby gaining sufficient momentum to withdraw the catch or arm 65 Q from the weight Q⁴ with certainty. It will also be seen that the weight Q⁴ falls from a

point above the rod P to a point below the same, or through about one-half of a circle, before coming in contact with the arm R² or its sleeve, thus gaining sufficient momentum 70 to release dog or catch R', with perfect certainty in all cases by a sharp well-defined stroke, in contradistinction to a gradual pulling action.

The feed-rolls and their mode of operation 75 are the same in the present machine as in that for which Letters Patent were granted to me as above stated; but the way in which the rolls are thrown out of operation differs somewhat, as will now be pointed out. As in said former 80 patent, the band-wheel J² is loose upon the shaft or axle J of the primary feed-roll, but is caused to rotate therewith, when desired, by a clutch, U, which is free to slide longitudinally upon the shaft J, but is held against rotation thereon by a spline or feather, as is customary in clutches of this class, the sleeve or sliding collar being moved in one direction by a spiral spring, V, encircling the shaft, and in a reverse direction by a cam, W, formed upon 85 the arm R and engaging with one end of the pivoted yoke or fork S, as more plainly shown in Figs. 5 and 7. Thus it will be seen that when the arm R is moved to separate the rolls, whether the same be effected automatically or 90 manually, the cam or incline W throws the clutch inward and causes its disengagement from the hub of the band-wheel J², permitting the latter to run free, and without operating the feed-rolls. When the arm R is again raised 95 to the position shown in Fig. 5, the incline riding away from the fork S permits the spring V to move the sleeve or clutch and to cause its re-engagement with the hub of the wheel J², said hub and clutch being preferably serrated or notched, as is usual, or, if preferred, made conical, or provided with friction-surfaces of any suitable construction. The shaft 100 J is furnished at the opposite side of the machine with an internally-toothed gear-wheel, 110 b, which gives motion to a pinion, b', secured upon the shaft of the second feed-roll, K'. The first or inner feed-roll, J³, is fluted longitudinally, and is preferably made of iron. It rotates at comparatively slow speed, and serves 115 to draw the material from the hopper and deliver it to the roll K', which I prefer to make of porcelain, and which, rotating more rapidly, carries the material over its top and delivers it, through the spout or hopper I², to 120 the crushing-rolls in a thin even stream or sheet, thus making the rolls to act upon each separate particle of the material evenly and uniformly. A trough or bottom, j, is hinged beneath the rolls J³ and K', to catch any material 125 which may pass between them. This trough or bottom may be readily released at its forward edge, where it is held by thumb-screws and permitted to fall down to discharge the material accumulated therein, or to give access to the feeding-rolls when desired.

In order to prevent the noise incident to the

use of gear-wheels, I employ gearing of the description claimed in my patent of April 19, 1881, No. 240,347, in which the wheels are formed with annular chambers and supplied with sand, shot, or other non-resonant substance. This gearing is peculiarly adapted to mills of this class, and overcomes almost completely the sound or noise hitherto so great an objection to geared roller-mills.

10 While I deem the construction and arrangement of parts herein described and illustrated as eminently satisfactory for the purpose of automatically stopping the feed and spreading the rolls whenever the material becomes nearly exhausted, it will be seen that other adaptations of the idea may be readily made by those skilled in the art; that various changes may be made, which, however, fall rather within the province of the mechanic than of the inventor. I therefore wish it understood that I do not limit myself to the precise details of construction herein set forth and shown; but I believe myself to be the originator of the broad idea of automatically disconnecting the feeding devices from their operating mechanism and spreading the rolls apart, or of automatically performing either of said operations when the material becomes low in the hopper, and therefore I claim such construction broadly and irrespective of the details of the mechanism by which such result is accomplished. As an illustration of one modified form of apparatus for this purpose, reference is made to Fig. 14, in which the shaft or rod P, on which 25 the gate or valve K is hung, is furnished with a combined cam and eccentric--that is to say, with a circular block, Q', set eccentric on the rod or shaft, and having its side face inclined relatively and not at right angles to the axis 30 of the shaft, the fork S by which the clutch is shifted being in such case inverted or placed above the feed-roll shaft, instead of below it, and operated by the inclined face of the block Q', and the tension device being jointed to an 35 upright lever pivoted at its lower end to the frame of the machine, and bearing at its upper end against the periphery of said block, as plainly indicated in Fig. 14. It will be 40 seen that under this construction the rise of 45 the gate or valve K, and the consequent rotation of the combined cam and eccentric, will cause the fork S to shift the clutch, and will also permit the tension device to move outward, relieving the swinging arms C' and permitting the separation of the rolls E and E'. When the supply of grain or material is 50 arranged within the hopper, the depression of the valve or gate K, turning the combined cam and eccentric, will permit the clutch to 55 be thrown into operative position through the action of its spring, and will also force or crowd back the upright arm, thereby restoring the adjustable roll E' to its working-position.

60 65 It is obvious that various other modifications of a similar nature may be made without

departing from the spirit of my invention; but the exemplifications herein shown and described are deemed sufficient to make said invention clear to those skilled in the art.

70

I am aware that a float or gate has before been arranged within a feed-hopper and connected with a regulating-gate in such manner that the opening and closing of the regulating-gate was controlled by the material in 75 the hopper. My plan differs from this, in that the variation of the supply does not alter the size of the discharge-opening; but when the material diminishes below a certain point, the feed-rollers, or other operating mechanism by 80 which the material is drawn out of the hopper, are automatically thrown out of action through the movement of a gate, valve, or board within the hopper.

Having thus described my invention, what I 85 claim is—

1. The combination, in a roller-mill, of a roller-adjusting mechanism, a feeding mechanism, a valve or gate arranged in the feeding-hopper and receiving the weight of the grain 90 or material to be operated upon, and intermediate connecting devices, substantially such as described, between said parts, whereby the rolls are spread and the feed cut off whenever the quantity of material in the hopper falls 95 below a certain predetermined point.

2. In combination with a feed-hopper, a feed-roll at the discharge-opening thereof, a driving-wheel detachably connected with said feed-roll, a valve or gate within the hopper, and an 100 intermediate connection, substantially such as shown and described, between the valve or gate and the driving-wheel of the feed-roll, whereby the movements of said valve or gate are caused to effect the connection and disconnection of the driving-wheel and feed-roll. 105

3. The combination of roll E, adjustable roll E', swinging arms C', hand-lever R, shaft or journal m, cross-shaft M', arms M, and slotted blocks M², secured upon said cross-shaft, and tension rods or frame L, and a locking device to hold the lever R in a fixed position, substantially as shown.

4. In combination with the hand-lever R, provided with cam or incline W, the feed-roll 115 shaft J, pulley J², clutch U, and fork S, all combined and operating substantially as described.

5. In combination with a roll-adjusting lever, R, the dog or catch R', provided with 120 arm R², gate K, shaft P, weighted arm Q², rigidly attached to said shaft, weight Q¹, dog or arm Q, and rod Q³, all combined and operating substantially as described.

6. In combination with the gate K, rod or 125 shaft P, weighted arm Q², weight Q¹, catch Q, rod Q³, lever R, provided with cam or incline W, dog R', provided with arm R², and weight l', feed-roll shaft J, band-wheel J², clutch U, and fork S.

7. The combination of a gate or board arranged to receive the weight of the grain or

130

material to be operated upon, feeding mechanism to deliver the material to the reducing apparatus, a driving-pulley for said feeding mechanism, and intermediate connections, substantially such as shown, for causing the driving-wheel to be disconnected from the gearing when the feed becomes low.

8. The combination of a gate or board arranged to receive the weight of the grain or substance to be operated upon, two grinding or reducing rolls, adjustable bearings for one of said rolls, and intermediate connections, substantially such as shown and described, between the gate or board and the adjustable bearings, whereby the rolls are caused to be separated when the feed becomes low in the hopper.

9. The combination of a gate or board arranged to receive the weight of the grain or substance to be operated upon, feeding mechanism arranged to deliver the material to reducing-rolls, a driving-pulley for the feeding mechanism, two reducing-rolls, adjustable bearings for one of said rolls, and intermediate connections, substantially such as shown, connecting the gate or board with the driving-pulley of the feed mechanism and with the adjustable bearings of the roll, whereby a diminution of the feed below a certain point is caused to simultaneously stop the feeding mechanism and separate the reducing-rolls.

10. In combination with roll E and its bearings, roll E', mounted in swinging arms C', pressure-springs g², arranged to bear against the outer side of the arms, and a second pair 35 of springs bearing against the inner sides of the arms, substantially as and for the purpose set forth.

11. In combination with roll E and its bearings, and with roll E' and its supporting-arms C', frames L L' L², springs g², screws g³, telescopic rods i', nuts i, springs h², and arms M, bearing against the cross-heads L², all substantially as shown and described.

12. In combination with a stationary roll, 45 an adjustable roll, and movable supporting-arms for the latter, springs arranged to bear against the movable arms and to press the movable roll toward the fixed roll, telescopic rods bearing against the supporting-arms at 50 one end, fixed supports at the opposite ends of said rods, springs encircling said rods, nuts screwed upon said rods, and arranged, substantially as shown, to support one end of the encircling-springs, and a frame, substantially 55 such as shown and described, carrying the rods and springs, and serving to keep them in place.

FRIEDRICH WEGMANN.
